E. HAUGEN

LARD DIPPER

Filed Oct. 13, 1924

UNITED STATES PATENT OFFICE.

EMIL HAUGEN, OF LAKE CRYSTAL, MINNESOTA, ASSIGNOR, BY DIRECT AND MESNE ASSIGNMENTS, OF FIVE-EIGHTHS TO ALFRED N. OLSON, OF LAKE CRYSTAL, MINNESOTA.

LARD DIPPER.

Application filed October 13, 1924. Serial No. 743,452.

This invention relates to a device especially designed for handling and measuring lard or butter or the like material designed primarily for use in the retail trade for permitting lard or analogous material to be handled and measured with the minimum amount of waste.

Another important object of the invention is to provide a device of this character which will be exceptionally sanitary, and one wherein it will be unnecessary for the person using the device to touch the material with his hands.

With the foregoing and other objects in view which will appear as the description proceeds, the invention resides in the combination and arrangement of parts and in the details of construction hereinafter described and claimed it being understood that changes in the precise embodiment of the invention herein disclosed, may be made within the scope of what is claimed, without departing from the spirit of the invention.

25 Referring to the drawing:

Figure 1 is an elevational view of a device constructed in accordance with the invention.

Figure 2 is a vertical sectional view 30 through the device, and taken on line 2—2 of Figure 1.

Figure 3 is a sectional view taken on line 3—3 of Figure 1.

Figure 4 is an enlarged detail view 35 disclosing the plunger rod and its bearing.

Referring to the drawing in detail, the reference character 5 indicates the tubular body portion of the device to which the rod 6 is connected and as shown, this rod is positioned adjacent to the discharge end of the body portion and divides the discharge end of the body portion.

Arms 7 are secured to the outer surface of the body portion and extend throughout the length of the body portion, the upper portion or horizontal section 8 forming a part of the arms being arranged in spaced relation with the upper end of the body portion 5 to provide a clearance for the plunger to be hereinafter more fully described.

An opening 9 is formed in the horizontal

section 8 and is surrounded by an upstanding flange 10 which is provided with cut out portions 11 to accommodate the pin 12 of 55 the plunger rod 13 so that the pin may be moved to a position within the cut out portions and permit the pressure exerted on the rod to force the device into material to be removed, and prevent the rod 13 from 60 being moved independently of the body portion 5.

The opening 9 is also provided with notches 14 to permit the pin to be moved through the opening and brought into engagement with the walls of the cut out portions 11 when it is desired to force the body portion into the material.

An inverted U-shaped bearing member is indicated at 15 and has connection with the 70 body 5 at 16, the upper or horizontal portion 17 of the member 15 being supplied with a suitable opening surrounded by the flange 18 to accommodate and act as a bearing for the rod 13. A handle 19 is mounted 75 on the upper end of the rod 13 and affords means whereby an operator may control the movements of the rod 13.

Mounted on the lower end of the rod 13 is the plunger 20 which may be moved to 80 a position adjacent to the upper portion of the body 5 when it is desired to fill the body portion 5, but acts to eject material contained in the body portion when the rod is moved in the opposite direction.

Forming a part of the plunger is an inwardly extended enlarged circular portion 6' having its inner surface spaced from the pin 12 so that when the plunger is moved to its innermost position, the pin 12 may 85 pass through the notches 14 associated therewith and drop into the cut out portion 11 to restrict movement of the plunger with respect to the section 8.

In the use of the device, the plunger is 90 moved to a position at the upper end of the body portion 5 and the rod 13 given a slight turn to cause the pin 12 to move through the notches 14 and into a position to engage the walls of the cut out portions 11 of the 100 flange 10. The device may now be forced into a container filled with lard or similar material, whereupon the device may be withdrawn. The rod 13 is now moved to cause

the pin 12 to pass through the notches 14 to the opposite side of the bearing or horizontal section 8.

A further movement of the rod 13 will cause the plunger to engage the material and force it from the body portion 5.

I claim:—

In a device of the character described, a cylindrical body portion, an inverted U-shaped member secured to the body portion and having the ends thereof extending to a point adjacent to the outer end of the cylindrical body portion, a second inverted U-shaped member having arms secured to the

body portion and disposed at right angles to the first mentioned inverted U-shaped member, the inverted U-shaped members being disposed in spaced relation with each other, a rod operating through the inverted U-shaped members and having a handle on its upper end, a plunger on the opposite end of the rod, said plunger adapted to operate in the body portion, to force material from the body portion.

In testimony that I claim the foregoing as my own, I have hereto affixed my signature.

EMIL HAUGEN.
